US00D644004S

(12) United States Design Patent
Nunn

(10) Patent No.: US D644,004 S
(45) Date of Patent: * Aug. 30, 2011

(54) GARMENT TOP

(76) Inventor: Daron D. Nunn, Bakersfield, CA (US)

() Term: 14 Years

(21) Appl. No.: 29/314,678

(22) Filed: Apr. 20, 2009

(51) LOC (9) Cl. 02-02

(52) U.S. Cl. D2/739; D2/840

(58) Field of Classification Search D2/717, D2/750, 840, 844, 720, 739, 828, 830, 841, D2/847; 2/106, 113, 115, 90, 93, 96, 108; D11/221

See application file for complete search history.
